UNITED STATES PATENT OFFICE

BENJAMIN F. FITCH, OF GREENWICH, CONNECTICUT, ASSIGNOR TO MOTOR TERMINALS COMPANY, OF WILMINGTON, DELAWARE, A CORPORATION OF DELAWARE

FREIGHT TRANSFER STATION

Application filed June 10, 1929. Serial No. 369,555.

This invention relates to a transfer station equipped and arranged for handling demountable automobile bodies, for readily unloading package freight from such bodies when loaded and for reloading package freight into unloaded bodies, and for the dispatch of the reloaded bodies. The station also provides for the convenient loading of the inbound packages into delivery carriers, and for the convenient receipt of freight from outbound carriers and its loading into the empty containers.

To the above end, I provide an inbound aisleway with a traveling crane adapted to remove loaded bodies from trucks at the end of the aisleway; I provide a parallel outbound aisleway equipped with a traveling crane to enable the freshly loaded body to be mounted on the truck, and to enable the lateral transfer of bodies from the inbound to the outbound aisleway, I prefer to employ transverse rows of floor rollers. Thus the bodies which have been deposited in the inbound aisleway and have been just emptied may be rolled into position in the outbound aisleway ready for reloading by package freight received on the outbound platform, and subsequently transferred to an automobile truck.

A feature of my invention is that I incline the roller-equipped platform downwardly from the inbound aisleway to the outbound aisleway, so that the demountable bodies may be rolled by gravity, or by manual power aided by gravity, from the aisleway where they are deposited by the inbound crane to the aisleway where they are to be lifted by the outbound crane. This provision raises the inner edge of the inbound platform and lowers the inner edge of the outbound platform, and this enables me to slope the inbound platform downwardly from its inner edge to its delivery edge, and to slope the outbound platform downwardly from its receiving edge to its inner edge, and thus gravity aids the hand trucking both from the received loaded containers to the delivery vehicle and from the receiving vehicle of package freight at the outbound platform

to the empty containers to receive the packages.

It will be seen that by means of the triple incline of the station floor as described I do away with the necessity of power mechanism to transfer the container from their inbound aisleway to their outbound aisleway and I also materially aid the hand trucking operations on both the inbound and outbound platforms.

I prefer to equip the intermediate or transfer platform not only with floor rollers but with suitable braking mechanism to engage the containers, so that I may have the floor steep enough to cause the ready rolling of the loaded containers by gravity without requiring manual force to shove the container. Accordingly, one or two operators controlling the respective brakes may quickly effect the transfer of the container from its receiving aisleway to its outgoing aisleway. The two aisleways are preferably of great enough height so that containers may be lifted over containers by the traveling cranes and thus the aisles may be kept full.

The aisles and traveling cranes are so arranged that the bodies are preferably trolleyed sidewise, and these bodies are provided with doors at opposite ends so that in loading the package freight on the outbound platform, such freight is transferred directly into the open end of the body from one or more vehicles at the opposite edge of the platform, or from the piles of packages temporarily deposited on the platform. Similarly at the inbound aisleway the freight is hand trucked through the open doors at the other ends of the bodies onto the inbound platform and there piled or carried to the delivery package carrier. As such carriers may not be available at the time the body is received, the inbound platform is made wider than the outbound, to provide more storage space.

The hand trucking may be between one package carrier to several bodies, or between several package carriers and one body, or between several carriers and several bodies, according to conditions and destinations. In any case, the packages are trucked "down

hill", thus increasing the speed of operation, and reducing the labor cost.

In the drawings, Fig. 1 is a sectional plan illustrating my transfer station in operation; 5 Fig. 2 is a sectional end elevation thereof; Fig. 3 is an end elevation of one of the containers; Figs. 4 and 5 are vertical sections illustrating one of the floor-rollers, showing also a portion of a container above such parts; 10 Figs. 6 and 7 are vertical sections illustrating one of the hand brakes; Fig. 8 is an elevation of the hand brake lever and its lock at right angles to Fig. 7.

As shown in Figs. 1 and 2, 10 indicates an 15 outbound platform, 20 an adjacent outbound aisleway, 30 a storage space, 40 an inbound aisleway and 50 an inbound platform. The outer edges of the outbound and inbound platforms are preferably at the same elevation, 20 and at the height of the floor level of the package receiving trucks A which may back up against the outbound platform, and the package delivering trucks B which may back up against the inbound platform. The outbound 25 platform inclines downwardly from its outer edge to its inner edge and the inbound platform inclines upwardly from its outer edge to its inner edge. The three intermediate aisles 20, 30 and 40 comprise a 30 substantially continuous single plane inclining from the inner or high edge of the inbound platform, to the inner or low edge of the outbound platform.

Along the edges of the various platforms 35 or aisle spaces are rows of columns as indicated at 11, 21, 22, 41, 42 and 51. These columns carry the ceiling braces 60 and the roof 61. The columns 21 and 22 also carry the outbound traveling cranes, and the columns 41 and 42 the inbound traveling cranes. Trackways for these cranes are supported on 40 brackets 23 and 43 carried by the proper columns on their inner sides and at a height above the corresponding platform somewhat 45 greater than twice the height of a demountable body. Traveling on these trackways are cranes 25 and 45, each of which preferably has four depending cables located at the four corners of a rectangle and adapted to engage 50 suitable hooks or eyes on the demountable bodies indicated by M.

The crane trackways overhang one or both ends of the station (Fig. 1 shows them overhanging one end) and beneath such overhanging portion is a runway for trucks adapted to deliver loaded bodies to the receiving aisle 40 and receive loaded bodies from the discharging aisle 20. A truck is shown at C at the inbound aisleway, its body 55 having been removed, and a truck D is shown at the outbound aisleway, the loaded body M having just been deposited thereon.

The intermediate floor space 20, 30 and 40 is equipped with rows of rollers 70 on which 60 the bodies may travel laterally "down-hill",

with suitable hand brakes to control such travel. A convenient form of roller and hand brake is illustrated in Figs. 6 to 8 incl. and will hereinafter be described in detail. For the present it need only be noted that these rollers are free to turn, at least in the direction from the inbound toward the outbound platform, and that they coact with a suitable track carried on the underside of the demountable bodies. Each body is preferably provided with several of these tracks; thus Fig. 3 shows three downwardly facing channel beams *m* furnishing the tracks.

When a container-carrying truck C arrives at the station, it stops at the end of the inbound aisleway 40 and the crane 45 is trolleyed over the truck. The loaded body is then lifted by the crane and trolleyed over the aisleway and deposited thereon. If another body is standing on the aisle in front of the space in which it is desired to position the arriving body, the latter body is raised and passed over the top of the standing body as indicated in Fig. 2. When deposited, the doors in the end of the body toward the platform 50 are open as shown at M' in Fig. 1, and the freight is hand-trucked out of the body, the hand truck being indicated at T. This freight may be deposited in piles on the inbound platform, as illustrated in Fig. 1, or it may be trucked directly to the receiving vehicle B; it may be trucked to different receiving vehicles, or freight from different bodies may be trucked to the same vehicle, as indicated by arrows in Fig. 1.

After a body has been unloaded, it is released and allowed to roll by gravity onto the intermediate storage space 30 or clear onto the outbound aisleway if there is a space vacant to receive it.

Whenever a package truck A arrives at the outbound platform its package freight may be deposited on the platform if necessary, but normally there are removable bodies standing in the outbound aisle with open end doors M' ready to receive the freight by hand trucking. Such hand trucking may be from one receiving truck to several containers or from several receiving trucks to one or more containers. When the container has been thus loaded, its doors are closed and the crane 25 carries it (over other containers if necessary) and deposits it on truck D. In normal operation, as soon as the truck C has been relieved of its body at the inbound aisle, it drives forward to the outbound aisle ready to receive a new loaded body.

It will be seen that the operation of removing a loaded body from a truck and depositing it on the platform, unloading the body for package delivery of its freight, transferring the body to the outbound aisle, reloading it, and depositing the loaded body on the outbound truck may be performed continuously and with great rapidity. The transfer

of the bodies from the inbound to outbound aisles, being effected principally or entirely by gravity, may be performed quickly and with little labor. The speed of the hand unloading and reloading is greatly increased by the fact that all of the manual trucking is done "down hill", and thus with little labor to the operator.

Should loaded bodies be received faster than they can be unloaded, so that the inbound aisleway is entirely full when a body is received, it is only necessary to allow a loaded body to roll onto the intermediate storage space; then, when an empty space is available in the inbound aisleway, this loaded body may be rolled by gravity to the outbound aisleway, transferred by the crane 25 to a waiting truck D, which will then back up into the space at the end of the inbound aisleway and the body may then be transferred by the crane 45 to an available space in that aisleway. On the other hand, if the outbound aisleway becomes crowded and it is not desired to dispatch the body to a distant station, it may be trolleyed onto the truck D thence backed to the inbound aisleway, trolleyed thereon to an open space and then rolled by gravity to an empty storage space on the intermediate aisle.

The floor rollers may be of any approved form and may be carried in the intermediate floor in any suitable manner. I prefer however to mount these rollers 70 (Figs. 4 and 5) tightly on short shafts 71 which have roller-bearings in a housing 72 which is mounted in a casing 73 set into the floor. The floor proper, indicated at 74 may readily be of cement, and the casing 73 embedded therein with an external flange portion 75 overhanging the

cement. The roller bearings for the floor rollers are carried in cavities 77 in the housing having end caps 78 as illustrated in Fig. 5. There, 80 indicates the inner race on the shaft; 81 nuts for holding such raceway in place; 82 the outer race way, and 83 rollers between the raceways. The outer races rest in circular seats in the housing proper.

The roller housing is preferably protected from dirt by a suitable cover. I have shown this as comprising a plate 85 overhanging the cavity occupied by the roller 70 and having a roughened top portion. Suitable screws 87 pass through the plate into the casing 72.

With the construction described, the different housings 73 may be embedded in the cement at the time the floor is laid, these housings being in rows transversely of the aisles. Then, after the floor with its housings 15 complete, the rollers with their entire bearings may be readily installed in the housings, and the covers put in place.

To lock the demountable bodies on the inclined transfer platform, either in the inbound aisle, the outbound aisle or the storage

aisle, as well as to control the passage down the incline from one aisle to the other, I provide suitable brakes mounted in the intermediate platform and adapted to coact with the container. There are preferably several of these brakes in a transverse row for each longitudinal container space, so that any container may be effectively controlled.

The brakes may readily be of the type shown in Figs. 6, 7 and 8 and comprise eccentric disks or shoes 90 keyed on operating shafts 91 to each of which is keyed a hand lever 92. The shafts 91 are shown as journalled in a suitably formed housing 93 embedded in the cement flooring 74. The shoes 90 are so positioned that they may readily engage the tracks m on the underside of the container and shove upward thereon when the shaft 91 is rocked. The hand lever 92 is shown as provided with a latch 95 controlled by a link 96 and hand grip 97. The latch coacts with teeth on a segment bar 98 secured to the housing 93. This arrangement enables the lever 92 to be locked in any desired position, wherefore the brake may be locked "on" or "off" as desired, or applied with varying force according to the manual pull on the lever 92.

Fig. 2 illustrates one row of the brakes, there being one brake shown for the container in the incoming aisle, one for the container in the outgoing aisle, and two for the container in the storage aisle. This brings the two brakes in the storage aisle close enough to the adjacent brakes in the two other aisles so that two brakes may engage the same container in transit from the incoming to the outgoing aisle. This enables a continual control of the container in such passage.

When the container is deposited on the incoming aisle and before the hoisting cables are loosened, the corresponding brake associated with that aisle is set and the container thereby locked. When it is desired to transfer this container by gravity, this brake is loosened slightly and the container rolled by gravity under the control of the brake until the advancing end thereof is over the first brake in the storage aisle; then, if desired, the latter brake may be set and control the descent until the container engages the second brake in this aisle, after which that brake controls the movement until the container arrives in the outgoing aisle, where it may be locked by the brake of that aisle.

The brake system described enables one man to control the descent of the container by successively applying and releasing the different brakes, although, for a more rapid operation, two men may be applying different brakes, thus enable the container to move without actual stopping from the incoming to the outgoing aisle.

It will be seen from the description given that my transfer station is of simple and com-

paratively inexpensive construction. At the same time, it enables the containers to be received, transferred and dispatched within a minimum of time. The speed of operation of the entire system is therefore dependent on the speed of hand trucking the packages from the received containers and to the outgoing containers, and this speed in each instance is increased by reason of the downward incline across which the hand trucking is effected. Accordingly, the entire system may be operated with the maximum of speed efficiency, and large and heavy packages transferred without delay.

The shippers' trucks are conveniently accommodated at the edge of the outgoing platform and the consignee's truck at the edge of the inbound platform and neither of them are obstructing the passageway for the trucks delivering and receiving the loaded bodies, and the time wasted by the latter truck is reduced to a minimum, as it need only be idle for the short interval while its body is being removed, the truck driven about two truck-lengths forward and the freshly loaded body deposited.

I claim:

1. A system of transferring freight by the means of removable vehicle bodies, comprising lifting a loaded body from a vehicle, transporting it to unloading position, trucking the contents of the body down hill to a delivery vehicle, then transferring the emptied body to a lower level, trucking a load from a receiving vehicle down hill to such lowered body, thereafter raising the freshly loaded body and depositing it on an outgoing vehicle.

2. A transfer station comprising an inclined platform, hoisting mechanism adapted to elevate a demountable body from a truck and deposit it on a higher portion of the platform where it may be unloaded, means for transferring the unloaded body by the aid of gravity to a lower region of the platform, where it may be reloaded, and hoisting mechanism adapted to raise the reloaded body and deposit it on a truck.

3. A transfer station comprising an inclined platform, two crane runways, one located over a higher portion of a platform and the other over a lower portion of a platform, cranes on the respective runways each adapted to elevate and transport a demountable body, and a truck runway extending transversely of the two crane trackways whereby a body on a truck may be removed by one crane deposited on a higher region of the platform shifted by the aid of gravity to a lower region of the platform, and thereafter deposited by the other crane on a truck in the truck runway.

4. A transfer station having an inclined platform, a traveling crane located over a higher portion of the platform, a paral-

lel traveling crane located over a lower portion of the platform, and a system of floor rollers extending transversely from the higher to the lower portions of the platform.

5. In a transfer station, the combination of an inclined platform, a pair of crane trackways parallel with each other located respectively over higher and lower portions of the platform, a truck runway at the end of the platform, the crane trackways extending over the runway, traveling cranes on said trackways, and transverse rows of rollers in the platform.

6. In a transfer station, the combination of a platform located intermediately in the station, a slightly inclined platform leading downwardly from one edge of the intermediate platform to one side of the station, a slightly inclined platform leading upwardly from the other edge of the intermediate platform to the other side of the station, and vehicle runways at the outer edges of the two outside platforms.

7. In a transfer station, the combination of a slightly inclined platform located intermediately in the station, the slightly inclined platform leading from the higher edge of the intermediate platform to one side of the station, the slightly inclined platform leading from the lower edge of the intermediate platform to the other side of the station, and means for depositing containers on a high region of the intermediate platform and removing them from a low region thereof.

8. In a transfer station, the combination of an inclined platform, two traveling crane trackways parallel with each other respectively located over higher and lower portions of the platform, cranes on the trackways, means for controlling the descent transversely of demountable bodies from the higher portion to the lower portion of the platform, and a pair of platforms one leading downwardly from the higher edge of the transfer platform and the other upwardly from the lower edge.

9. In a transfer station, the combination of a slightly inclined platform located intermediately in the station, the slightly inclined platform leading from the higher edge of the intermediate platform downwardly to one side of the station, a slightly inclined platform leading from the lower edge of the intermediate platform upwardly to the other side of the station, and vehicle runways at the outer edges of the two outside platforms, traveling cranes extending longitudinally over the higher portion and lower portion of the intermediate platform, tracks for said traveling cranes projecting beyond an end of the intermediate platform and over a truck runway at such end.

10. In a transfer station, the combination of a slightly inclined platform located inter-

mediately in the station, a slightly inclined platform leading from the higher edge of the intermediate platform to one side of the station, a slightly inclined platform leading from the lower edge of the intermediate platform to the other side of the station, and lanes of floor rollers located in the intermediate platform extending transversely from the higher region thereof to the lower region.

11. In a freight transfer station, the combination of an intermediate platform having an inbound aisle and an outbound aisle with their floors in a plane inclining downwardly from the inbound aisle to the outbound aisle, an inbound platform inclining downwardly from the inbound aisle, an outbound platform inclining downwardly to the outbound aisle, lanes of floor rollers extending transversely on the inclined platform from the upper to the lower aisle, traveling cranes located over such upper and lower aisles, and a truck runway over which the traveling cranes are adapted to move.

12. In a freight transfer station, an inclined platform having an inbound aisle on its higher portion and an outbound aisle on its lower portion and a storage aisle between the inbound and outbound aisle, means for positioning containers on the inbound aisle, such containers being adapted to be moved by gravity from the inbound aisle to the storage aisle and thence to the outbound aisle, means for controlling the descent, and means for removing containers from the outbound aisle.

13. The combination with automobile trucks and mountable automobile bodies having trackways on their undersides, of a transfer station having an inclined platform and means for transferring bodies from a truck to an aisle extending along the upper portion of a platform, rows of floor rollers leading transversely from the upper portion of the platform to the lower, said floor rollers being adapted to coact with the tracks on the undersides of the demountable bodies, and means adapted to deliver bodies arriving by gravity at the lower aisle.

14. In a transfer station, the combination of a slightly inclined platform providing an inbound aisle along the higher portion of the platform and an outbound aisle along the lower portion, a pair of traveling cranes over the respective portions, said cranes being supported at such elevation above the platform that they may lift one body over another body on the platform, whereby bodies received at the end of the inbound aisle may be deposited at any position thereon and bodies may be removed from any portion of the outbound aisle and deposited on an outgoing vehicle, said bodies being movable by the aid of gravity from the inbound to the outbound aisle.

15. In a freight transfer station, the combination of an inclined platform providing an inbound aisle along the upper portion of the platform and an outbound aisle along the lower portion, crane trackways over the respective aisles, traveling cranes on the respective trackways supported above the platforms a distance greater than twice the height of a removable body, a truck runway spanned by such trackways, whereby one crane may remove a body from a truck in the runway, transport it over other bodies in the inbound aisle and deposit it on the platform, and the other crane may remove a body from the outbound aisle, transport it over other bodies and deposit it on a truck in the runway, and floor rollers in the intermediate platform arranged in transverse rows and spaced to coact with trackways on the undersides of the containers deposited on the platform.

16. In a freight transfer station, the combination of an inclined platform providing an inbound aisle along the upper portion of the platform and an outbound aisle along the lower portion, crane trackways over the respective aisles, traveling cranes on the respective trackways supported above the platforms a distance greater than twice the height of a removable body, a truck runway spanned by such trackways, whereby one crane may remove a body from a truck in the runway, transport it over other bodies in the inbound aisle and deposit it on the platform, and the other crane may remove a body from the outbound aisle, transport it over other bodies and deposit it on a truck in the runway, a downwardly inclined side platform leading from the high edge of the intermediate platform to one side of the building, an upwardly inclined side platform leading from the lower edge of the intermediate platform to the other side of the building, and vehicle runways at the outer edges of the two side platforms.

17. In a freight transfer station, the combination of an intermediate platform having an inbound aisle and an outbound aisle having their floor inclining downwardly from the incoming aisle to the outgoing aisle, an inbound platform inclined downwardly from the inbound aisle to the delivery edge of the building, an outbound platform inclining downwardly from the opposite side of the building to the lower edge of the outbound aisle, rows of floor rollers extending transversely on the inclined platform from the upper to the lower aisle, and a series of brakes mounted in the platform and arranged in transverse rows adapted to coact with the containers.

18. The combination with automobile trucks and demountable bodies having trackways on their undersides, of a transfer station having an inclined platform and means

for transferring bodies from a truck to an aisle extending along the upper portion of a platform, rows of floor rollers arranged in parallel groups and leading transversely from the upper portion of the platform to the lower, said floor rollers being adapted to support the demountable bodies and rows of brakes for controlling the passageway of the bodies from the upper aisle to the lower aisle.

19. In a freight transfer station, the combination of an inclined platform having an inbound aisle along its upper portion and an outbound aisle along its lower portion, means for guiding containers transversely from the upper aisle to the lower aisle, brake shoes eccentrically mounted on rock shafts carried by the platform, levers for operating the rock shafts to cause the brake shoes to engage the containers, and means for positioning such containers on the inbound aisle and for removing such containers from the outbound aisle.

20. In a freight transfer station, the combination of an inclined platform having an inbound aisle along its upper portion and an outbound aisle along its lower portion, transverse rows of rollers supported by rolling bearings leading from the upper aisle to the lower aisle, containers having on their undersides trackways adapted to register with such transverse rows of rollers and means for positioning such containers on rollers in the inbound aisle and means for removing such containers from rollers in the outbound aisle.

21. The combination with automobile trucks and demountable bodies, of a transfer station having a slightly inclined platform, means adapted to remove a body from a truck and place it sideways on the upper portion of the platform, means adapted to remove a body from the lower portion of the platform and place it on a truck, means for transferring a body laterally from the upper portion of the platform to the lower, said bodies having doors at the opposite ends thereof whereby either end of the body may be opened, an inbound platform inclining downwardly from the higher edge of the intermediate platform and an outbound platform inclining downwardly to the lower edge of the intermediate platform, said inbound and outbound platforms being adapted for hand trucking of packages from the incoming containers through one end thereof and into the outgoing containers through the opposite end thereof.

22. The combination with automobile trucks and demountable bodies having trackways on their base, of a transfer station having a slightly inclined platform across the end of which the trucks may drive, a traveling crane adapted to remove a body from a truck and transfer it sideways onto the up-

per portion of the platform, a traveling crane adapted to remove a body from the lower portion of the platform and transfer it sideways onto a truck, a system of floor rollers leading transversely from the upper portion of the platform to the lower, said rollers being adapted to engage the tracks at the bottom of the bodies, said bodies having doors at the opposite ends thereof whereby either end of the body may be opened, an inbound platform inclining downwardly from the higher edge of the intermediate platform and an outbound platform inclining downwardly at the lower edge of the inclining platform, said inbound and outbound platforms being adapted for hand trucking of packages from the incoming containers through one end thereof and into the outgoing containers through the opposite end thereof.

23. The system of transferring freight by removable bodies comprising removing a loaded body from a vehicle and depositing it on a station platform, trucking freight from the body down hill, reloading it by trucking freight down hill to the body, thereafter mounting the reloaded body on a vehicle.

24. A system of transferring freight by the means of removable automobile bodies, comprising lifting a loaded body from a vehicle, transporting it to unloading position, trucking the contents of the body down hill to a delivery vehicle, trucking a load from a receiving vehicle down hill to such lowered body, thereafter raising the freshly loaded body and depositing it on an outgoing vehicle.

25. In a transfer station, the combination of a slightly inclined platform located intermediately in the station, a slightly inclined platform leading downwardly from the high edge of the intermediate platform to one side of the station, a slightly inclined platform leading upwardly from the lower edge of the intermediate platform to the other side of the station, and vehicle runways located respectively at the outer edges of the two outside platforms and depressed substantially the same distance below the level of such edges.

26. The combination of a transfer station having an intermediate platform, an inbound platform inclining downwardly from one edge of the intermediate platform, an outbound platform inclining upwardly from the opposite edge of the intermediate platform, a set of demountable vehicle bodies having doors in opposite walls thereof, and mechanism for placing such bodies on the intermediate platform so that there may be downhill hand trucking of packages discharged through one door of the body and downhill trucking of packages for loading into the body through the opposite door.

27. A transfer station having an intermediate platform, an inbound platform inclining downwardly from one edge of the intermediate platform, an outbound platform inclining upwardly from the other edge of the intermediate platform, vehicle runways adjacent the free edges of the outbound and inbound platforms, a vehicle runway adjacent the end of the intermediate platform, and mechanism for transferring a demountable vehicle body between a vehicle in the last mentioned runway and the intermediate platform.

In testimony whereof, I hereunto affix my
signature.

BENJAMIN F. FITCH.
